MONTFORD MORRISON, OF MONTCLAIR, NEW JERSEY, ASSIGNOR TO WESTINGHOUSE X-RAY COMPANY, INC., A CORPORATION OF DELAWARE

TERMINAL BUSHING

Application filed August 22, 1931. Serial No. 558,873.

My invention relates to high tension insulating bushings and has particular reference to insulating bushings of the general type commonly utilized for conducting the 5 high tension current from an encased oil immersed source of high potential electrical energy to the exterior thereof.

Various types of insulating bushings are well known to the art which are usually constructed of ceramic material having a high 10 dielectric strength but these devices are fragile and costly to construct.

It is an object of my invention to provide a high tension insulating bushing having a 15 high dielectric strength and which is economical to manufacture.

Another object of my invention is to provide a high tension insulating bushing which will withstand corona effects and all 20 electrical stresses to which the insulator may be subjected.

Still further objects of my invention will become apparent by reference to the accompanying drawing wherein the single figure 25 illustrates an elevational view in section of my high tension insulating bushing.

Referring now to the drawing in detail I have shown in the figure a casing 5 adapted 30 to surround a high tension source of electric energy such as a transformer (not shown). An oil tight cover plate 6 is arranged to be firmly secured to the casing 5 and an insulating and cooling material, such as oil 7, is arranged to immerse the high tension source.

35 A metallic annular ring 8 is rigidly secured to the cover plate 6 by suitable means, such as rivets or bolts 9.

A metallic conductor 10 is concentrically disposed within the opening of the annular 40 ring 8 and is in turn surrounded by an insulating material 12 of high dielectric strength, but which is deleteriously affected by contact with oil.

This material 12 may be of a mixture, such 45 as resin, beeswax and paraffine or other analogous substances having the desired dielectric strength. The metallic conductor 10 and insulating material 12 extends a substantial distance above and below the annular ring 50 8 and at its lower extremity is arranged to

protrude into the cooling and insulating medium, such as the oil 7.

The composition of the aforementioned insulating material being deleteriously affected by contact with the oil is, therefore, 55 prevented from actual contact therewith by a second high tension insulating material, such as varnished cambric, paper or a phenolic condensation product 13 having a high dielectric strength. This latter insulating 60 material 13 is wound in the form of spirally successive layers which increase in diameter toward the annular ring 8 at which point the electric stresses are greatest due to the close proximity of the high tension metallic 65 conductor 10 to the annular ring 8 which is in common practice usually grounded.

The insulating material 13 at the point 14 extends a substantial distance longitudinally of the insulating material 12. The diameter at this point is of such dimensions 70 as to fit tightly within the annular ring 8 and serves to support the insulator within the cover plate 6.

In order to make the entire insulator of 75 uniform diameter which corresponds to the internal diameter of the annular ring 8 the insulating material 12 is of slightly less diameter over that portion in which the wrapped insulating material 13 is superimposed in order that the combined insulating 80 materials equal the interior diameter of the annular ring 8, and the diameter of the insulating material 12. The insulating material 13 is provided with a portion 15 immediately above the annular ring 8 of an increased diameter than the remaining portions of the insulator which, together with the tightness of the insulator in passing through the annular ring, assists in supporting 85 the entire insulator within the cover plate. The metallic conductor 10 is threaded at both of its extremities and suitable washers 16 and nuts 17 are arranged to hold the metallic conductor firmly within the insulator and for the purposes of connecting the respective lead wires to the insulator.

A petticoat portion 18 is provided at the upper extremity of the insulator for the purpose of protecting the insulator from cli- 100

matic conditions when the same is used in outdoor construction.

My insulator may be molded of the material which is deleteriously affected by the oil and then wrapped with the material which is unaffected by the oil. This latter material may be applied after the insulator has been positioned within the cover plate and if desired the material 13 may be dipped 10 in an oil resisting compound to increase the resistance of the material, or this dipping may be dispensed with, if desired, by selecting the proper insulating material.

It can, therefore, be readily seen that I 15 have constructed a high tension insulating bushing which has a high electric strength and in which the greater portion thereof may be constructed of a non-oil resisting compound and a portion thereof covered with an 20 oil resisting insulating material to prevent the insulator from actually contacting the oil immersing the high tension source.

By selecting materials that are deleteriously affected by contact with oil but which 25 have a higher dielectric strength than the usual materials employed, which are unaffected by contact with the oil, such as ceramic materials, and covering a portion of the same by an oil resisting insulating material, 30 my entire insulator can be more economically manufactured than those of the prior art.

Although I have shown and described one specific embodiment of my invention I do 35 not desire to be limited thereto as various other modifications of the same may be made without departing from the spirit and scope of the invention as set forth in the appended claims.

40 **What is claimed is:**

1. In combination with a casing for an oil immersed high tension source, a high tension insulating bushing comprising a high tension conductor, a high tension insulating material deleteriously affected by oil surrounding said conductor and a high tension insulating material unaffected by contact with oil, spirally wound about one extremity of said first mentioned insulating material and 45 in contact with the oil immersing said high tension source to prevent the deleteriously affected insulating material from contacting the oil immersing said high tension source.

2. In combination with a casing for an oil 55 immersed high tension source, a high tension insulating bushing comprising a high tension conductor, a non-oil resisting high tension insulating material having a dielectric strength greater than oil resisting insulating material surrounding said conductor, and a high tension oil resisting insulating material superimposed in successive layers upon a portion of said first mentioned insulating material and in contact with the oil 60 immersing said high tension source to pre-

vent the non-oil resisting insulating material from contacting the oil immersing said high tension source.

3. In combination with a casing for an oil immersed high tension source, an oil tight cover plate for said casing, a high tension insulating bushing secured to said cover plate and extending above and below the same, comprising a high tension conductor, a non-oil resisting high tension insulating material having a high dielectric strength surrounding said conductor and extending substantially the entire length thereof, and an oil resisting high tension insulating material spirally wound in successive layers about the portion of said first mentioned insulating material disposed below said cover plate and in contact with the oil immersing said high tension source.

4. In combination with a casing for an oil immersed high tension source, a high tension insulating bushing comprising a high tension conductor, a high tension insulating material having a high dielectric strength and deleteriously affected by oil surrounding said conductor, and a high tension insulating material unaffected by oil wound in successive layers upon a portion of said first mentioned insulating material to prevent the same from contacting the oil immersing 95 said high tension source.

5. In combination with a casing for an oil immersed high tension source, a high tension insulating bushing comprising a high tension conductor, a high tension insulating material having a high dielectric strength and deleteriously affected by oil surrounding said conductor, and a high tension insulating material unaffected by oil spirally wound in successive layers upon a portion 100 of said first mentioned insulating material to increase the diameter of said last mentioned insulating material upon application of each successive layer until a maximum is reached at the point where the electrostatic stress is greatest and said last mentioned insulating material being in contact with the oil immersing said high tension source.

In testimony whereof, I have hereunto 115 subscribed my name this 17th day of August, 1931.

MONTFORD MORRISON.
